UNITED STATES PATENT OFFICE.

C. F. J. MOLLER AND C. LATHAM SHOLES, OF MILWAUKEE, WISCONSIN.

IMPROVED SHOE-BRUSH.

Specification forming part of Letters Patent No. 57,168, dated August 14, 1866.

To all whom it may concern:

Be it known that we, C. F. J. MOLLER and C. LATHAM SHOLES, of the city and county of Milwaukee, State of Wisconsin, have invented a new and useful Improvement on the Shoe-Brush now ordinarily in use; and we do hereby declare that the following is a full, clear, and exact description of the same, reference being had to the annexed drawing, wherein—

A represents the blade or scraper, and B the brush with the blade or scraper attached, making part of this specification.

The edge-line from c to d represents nearly the arc of a circle, which adapts it the more readily to the rounded shape of the boot. The point c is intended to operate between the sole and upper leather, and the end f is calculated for cleaning the edge of the sole.

We construct our improvement or invention by taking or manufacturing the shoe-brush in any of the forms or styles in use, and attaching to either side of the same a blade or scraper

substantially of the form of the drawing annexed, which, in the hands of the operator of the brush, may be conveniently used for the purpose of removing any dirt or foreign substance from the object operated on.

Having thus described our invention with such particularity as it is susceptible of, we disclaim inventing the brush in any of its forms; but

We claim—

The construction and arrangement of the scraper, in combination with the brush, as herein described, consisting of the end f, for cleaning the edge of the sole, the point c, for cleaning between the sole and upper, the curvilinear edge from c to d, and attached to the side of the brush, for the purposes set forth.

C. F. J. MOLLER.
C. LATHAM SHOLES.
